UNITED STATES PATENT OFFICE.

ASA E. TARBOX, OF OAKLAND, CALIFORNIA.

SIGN CHARACTER.

Application filed July 23, 1927. Serial No. 207,898.

The invention forming the subject matter of this application relates to sign letters or the like characters.

Signs of the illuminated type in present use are generally of hollow construction, so as to permit the employment of a large number of electric light bulbs to be placed in the hollow of the letters so as to transmit the light rays through the translucent face of the sign. Reflectors are usually disposed behind the electric lights to reflect the artificial or natural rays to enhance the attractiveness and brightness of the sign.

An object of the present invention is to provide a sign letter constructed from a large number of mirrored glass fragments solidly secured in a frame and disposed randomly and angularly to each other, whereby the reflection of the natural or artificial light rays is accomplished without necessitating the present hollow construction and the use of the large number of electric bulbs and separate reflectors therefor.

Another object of the invention is to provide a sign letter whose construction is simple, massive and attractive, so as to obviate the employment of the complicated electric wiring and the connections thereof and substitute a sign therefor which is illuminated exteriorly by the natural or artificial light rays.

A further object of the invention is to provide a sign having its letters or characters promiscuously reflecting light rays in all directions, thereby rendering the characters visible from all points of view.

A still further object of the invention is to provide a sign made up of letters constructed of small bits of mirrored glass randomly disposed out of plane alignment to create a continual state of reflection therefrom and produce a dazzling effect.

With these and other objects in view, which will more readily appear as the nature of the invention is better understood, the invention consists in the novel construction, combination and arrangement of parts, which will hereinafter be more fully described, illustrated and claimed.

The essential features of the invention involved in the carrying out of the objects indicated are susceptible to modification; but a preferred embodiment of the invention is shown in the accompanying drawings, in which:

Figure 1 is a front view of a letter of a

sign constructed in accordance with my invention; and

Fig. 2 is a cross-section of it taken along either of the lines 2—2.

Referring to the accompanying drawings, the invention comprises a facing 1 having a recess 2 therein. The recess 2 is of dovetail cross-section and describes the outline of any desired character such as the letter E shown in Fig. 1. Adhesive 3 is adapted to be poured or otherwise placed in the recess 2, and before the adhesive dries and hardens, bits of mirrored glass 4 are bedded therein. The mirrored glass 4 is of common construction and is made up of the transparent glass portion 5 and the reflecting coating 6. When the bits of mirrored glass are imbedded in the adhesive, the reflecting coating 6 is adjacent the adhesive and the transparent glass portion is disposed to the light rays.

As it is clearly illustrated in the drawings, the bits of mirrored glass 4 are just fragments of variable shape and size and are disposed at an angle to each other. Thus, the light rays striking the mirrored glass from any direction are reflected therefrom and create a dazzling and irregular brilliancy. Due to the light striking and reflecting from each separate bit of mirrored glass, the sign is in a continual state of reflection.

It is evident that the artificial lighting of the sign can be greatly enhanced by flood lights disposed away from the sign itself but directed thereon.

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made, when desired, as fall within the scope of the appended claims.

Having thus described my invention, I claim as new and desire to secure by Letters Patent of the United States, the following:

1. In a sign comprising a foundation having a recess therein forming the outline of a letter or other character at a surface thereof, a plurality of members providing reflecting surfaces and fixed in said recess with their reflecting surfaces directed outwardly

thereof and in mutually random relation, the outer faces of said members being disposed to generally define a surface comprising a continuation of said foundation surface across the mouth of said recess.

2. In a sign, a foundation having a recess therein forming a plane outline of a letter or other character, and a plurality of members providing reflecting surfaces and fixed

in said recess with the reflecting surfaces of adjacent members differently and randomly directed outwardly of the recess, the outer faces of said members being disposed to generally define a plane surface at the mouth of said recess.

In testimony whereof, I affix my signature.

ASA E. TARBOX.
